STRAND STORE DEVICE

Frank L. Durr, New York, N. Y.

Application May 15, 1956, Serial No. 585,067

4 Claims. (Cl. 203—280)

This invention relates to a thread or strand storage device of the reel type adapted to take on a strand at one end, feed the strand in spiral form along the length of the device and discharge the strand at the opposite end.

Among the objects of the invention is to provide a strand storage device of the type specified in which the strand which is stored thereon is not under tension and does not bind the parts of the reel in any way.

Among other objects of the invention is to provide a thread or strand storage reel which is adapted to operate with different strand materials having high variations of flexibility, with strand materials of various degrees of elasticity and with strands of relatively thick cross sectional areas.

While the strand material is being stored it may be treated with various liquid treating agents.

The objects of the invention are attained by providing a two part combination reel, a first part of which rotates inside of the second part, the first part of which is adapted to carry the strand on its outside surface and the second part of which is adapted to carry the strand material on its inside surface. One reel part is made to rotate in a circular or elliptical path which is at an angle to the circular path of the other reel part. When the strand material rests on the first reel part it moves in a different direction than when it rests on the second reel part. The said second reel part is rotatably supported from the outside. The two parts are rotated so that the peripheral speed of the outside surface of the first part is substantially equal to the peripheral speed of the inside strand contacting surface of the second part.

The combination reel may be used for temporarily storing a large tow or bundle of threads, flexible wires, a linear woven or knitted fabric, etc.

The reel combination may be positioned in a bath for dip treating the strand being stored or the strand material may be sprayed with the desired treating liquid or with drying air, for example, during storage.

Examples of treatments which may be applied to the strand are dyeing, desulfurizing, bleaching, drying, in the case of yarns and fabrics or pickling, electroplating, etc. in the case of metal strands.

The invention together with additional objects and advantages thereof will be better understood from the following examples of a specific embodiment thereof when read in connection with the accompanying drawing wherein:

Fig. 1 is a side view of the storage device.

Fig. 2 is an end view of the device dipping into a treating bath.

Fig. 3 is a detail view of a part of the outside reel portion.

The storage device of the invention comprises an inside reel or roller portion 10 and an outside reel portion 30. The strand material 50, which is illustrated, is a relatively flexible bundle of fibers, but any type of strand material capable of hanging in a series of loops about the central

2

roller 10 may be stored although a stiffer bundle or strip material will not hang as loosely as the bundle 50 which is illustrated.

The outside portion 30 is reel shaped but in some instances may have a continuous inside surface instead of being formed of bars 31 as shown. The inside roller 10 and the reel 30 are rotated so that the peripheral speed of the outside of roller 10 equals the speed of one of bars 31 of the reel 30, or in other words the parts of the two portions 10 and 30 which together carry the strand material 50 travel at substantially the same speed. However, these two portions do not travel in concentric paths although the roller 10 is approximately the same length as the reel 30 and is approximately symmetrically positioned within said reel 30. While the strand material is moving along with the upper part of roller 10, it is also moving axially (to the right as shown in Fig. 1) with respect to reel 30, and/or conversely when the strand material 50 is resting on the lowermost rods 31 of reel 30 and moving therewith, it is moving axially (to the right as shown) with respect to roller 10. This effect may be obtained (especially when the length of the store device is short compared to the diameter of the outside reel) by simply mounting the inside roller 10 and the outside portion 30 (which in this case may be continuous and cylindrical in form) to rotate about substantially horizontal axes located in different vertical planes which cross each other.

In the device shown the roller 10 rotates about a substantially horizontal axis 11—12 and each point on the reel 30 rotates about the roller 10 as if the point were mounted on a substantially horizontal axis which is in a vertical plane at an angle to the vertical plane of axis 11—12 of the portion 10. However, the rods 31 are so mounted on reel member 30 and the reel itself is mounted on pulleys or rollers 32, 33, 34, etc. that rods 31 oscillate axially back and forth once, with respect to the roller 10 during each rotation. This effect is obtainable by virtue of the pivotal mounting of the rods 31 on the rings 35, 36, by links 36 which are pivotally attached to the rods as shown in Fig. 3. In this way the rollers 32, 33, 34, etc. which in effect guide the axial movement of the rods 31 during rotation may be adjusted to give different degrees of axial movement with each rotation.

As shown in Fig. 2, guide pulleys or rollers 33 and 34 may be positioned inside a bath or container 40 capable of holding treating liquid 45 for the material 50. Rollers 34, for example, may be mounted in bath 40 by means of brackets 41, 42. The member 30 may be rotated by driving one or more of the rollers 32, 33, 34, etc. The inside roller 10 is driven from the axle 11 or 12. As stated above the two members are driven at such a speed that the outside peripheral speed of roller 10 equals the speed of the inside surface of one of rods 31. If it is not convenient to drive one of rollers 32, 33, 34, the reel member 30 may be driven by an endless belt passing partially around the same.

As shown in Fig. 1, the bundle of fibers 50 is fed onto the top portion of roller 10 and allowed to pass downwardly until it contacts a bar 31. The bar 31 carries the bundle around and to the right (as shown in Fig. 1) and when the bundle next passes to the surface of roller 10 it is axially spaced from the region where the bundle first contacts said roller 10, and so on with each loop of the bundle 50. The bundle may be threaded onto the device by attaching an end thereof to a continuous, more or less flexible, ring of approximately the diameter and size of one spiral turn of the bundle within the store device.

The features and principles underlying the invention described above in connection with specific exemplifications will suggest to those skilled in the art many other

modifications thereof. It is accordingly desired that the appended claims shall not be limited to any specific feature or details thereof.

I claim:

1. In a store device of the type adapted to take up a strand of linear material at one end feed said strand axially along the store device and deliver the strand at the opposite end thereof, a first member mounted for rotation about a first axis and having strand-contacting means on the outside surface thereof, a second rotating member surrounding the first member and having strand contacting means on the inside thereof, means outside of said second rotating member for rotatably mounting the same, said last named means being positioned to rotate said second member so that each point thereof moves once back and forth axially with respect to the first member with each complete rotation. 15

2. The device as set forth in claim 1 in which said means for rotatably mounting the second member comprises at least three pulley members, said second member comprising at least one ring outside the strand contacting means adapted to be guided in said pulleys.

3. The device as claimed in claim 1 in which said first member comprises a substantially continuous cylindrical roller.

4. The device as claimed in claim 1 in which said strand contacting means of said second member consists of a plurality of rods extending lengthwise of the member, at least two rings extending around said rods and means pivotally connecting the rings to each of said rods.
